UNITED STATES PATENT OFFICE.

FREDERICK G. STICKLES, VALENTINE M. MILLER, AND LESLIE WACKEROW, OF
MELLETTE, SOUTH DAKOTA.

WRENCH.

1,174,907.

Specification of Letters Patent. Patented Mar. 7, 1916.

Application filed June 2, 1914. Serial No. 842,401.

To all whom it may concern:

Be it known that we, FREDERICK G. STICKLES, VALENTINE M. MILLER, and LESLIE WACKEROW, citizens of the United States, 5 residing at Mellette, in the county of Spink and State of South Dakota, have invented certain new and useful Improvements in Wrenches, of which the following is a specification.

10 This invention has for its object to provide a wrench embodying a body, pivoted jaw and pivoted handle for adjusting the pivoted jaw.

Another object is to provide a wrench 15 having a handle adjustable angularly relative to the body thereof.

With these and other objects in view, the invention consists in the novel construction, arrangement and combination of parts as 20 will be hereinafter specifically described, claimed and illustrated in the accompanying drawings, in which,

Figure 1 represents a side elevation of the wrench, and, Fig. 2 represents a top plan 25 view thereof. Fig. 3 represents a fragmental detail sectional view of the locking means for the pivoted jaw.

Referring to the drawing in detail, where- 30 in similar reference numerals designate cor- responding parts throughout the several views, the numeral 5 indicates the body of the wrench consisting of two parallel bars secured together centrally by a pin 6 and se- 35 cured at one end in spaced relation by a pin 7. The free ends of the parallel body mem- bers are formed to provide a pair of spaced 40 relatively stationary jaws 8 having suitable teeth 9 on their working faces. Between the parallel body members 5 a relatively mov- 45 able jaw 10 is pivotally secured on the pin 6 and provided with a concentric face hav- 50 ing teeth 11 thereon. The working face 12^a is preferably of angular formation, as clearly illustrated in Fig. 1, provided with a plurality of teeth similar to the teeth 9.

A handle 12 is provided with an enlarged 55 end 13 positioned between the parallel body members 5 and pivotally mounted on the pin 7. The enlarged end 13 is formed con- 60 centrically with the pivotal axis 7 of the handle, and provided with teeth adapted to mesh with the teeth 11 of the movable jaw

whereby the movable jaw is adjustable as desired, relatively to the jaw 8.

The adjustable jaw 10 is provided adja- 55 cent the teeth 11 with a plurality of recesses 15, in one of which the inner end of a pin 16 is normally retained by the tension of a spring 17. The pin 16 is provided with a head 18 whereby said pin may be conven- 60iently withdrawn from the recesses 15 to adjust the jaws of the wrench as desired.

It is frequently desirable to change the relative angular position of the body 5 and the handle 12 of the wrench, and to accom- 65 plish this the movable jaw 10 is rotated in the direction of the arrow of Fig. 1 until the teeth 11 thereof are moved out of mesh with the teeth on the enlarged end 13 of the handle. With the parts in this position it 70 is apparent that the handle 12 may be moved to any position relative to the body 5 and the jaw 10 subsequently rotated to opera- 75 tively mesh the teeth of the handle and the jaw.

What we claim is:—

In a wrench having a body member, a jaw formed on the outer portion of said body member, a relatively movable jaw piv- 80 otally mounted to said body member, a han- dle pivotally secured to the body member, said handle and movable jaw being opera- 85 tively connected, said relatively movable jaw having a series of vertical recesses ar- ranged concentrically to its pivotal axis and adjacent the inner edge thereof, said body member having a vertical aperture 90 formed therein in alinement with said re- cesses, a pin slidably mounted in said aper- ture and adapted to engage in any one of said recesses, thereby locking said jaws, means to normally hold said pin in engage- 95 ment with said recesses, and a head on said pin whereby said pin can be withdrawn from engagement with said recesses thereby al- lowing said jaws to be adjusted.

In testimony whereof we affix our signatures in presence of two witnesses.

FREDERICK G. STICKLES.
VALENTINE M. MILLER.
LESLIE WACKEROW.
